(57) CLAIM

I claim the ornamental design for a beverage can with a portion of a mural, as shown and described.

DESCRIPTION

FIG. 1 is a perspective view of a beverage can with a portion of a mural, showing my new design;

FIG. 2 is a front elevational view thereof;

FIG. 3 is a rear elevational view thereof;

FIG. 4 is a right-side elevational view thereof;

FIG. 5 is a left-side elevational view thereof;

FIG. 6 is a top plan view thereof;

FIG. 7 is a bottom plan view thereof; and,

FIG. 8 is a bottom perspective view thereof.

The broken lines showing a mural image and additional beverage cans in FIG. 1 and bottom elements in FIGS. 7 and 8 depicts environmental matter and forms no part of the claimed design.
